BALL POINT PEN

Charles K. Lovejoy, Atlanta, Ga., assignor to Scripto, Inc., a corporation of Georgia

Filed July 12, 1960, Ser. No. 61,319

Term of patent 14 years

(Cl. D74—17)

FIG. 1 is a rear elevational view of the ball point pen embodying my new design;

FIG. 2 is a front elevational view thereof;

FIG. 4 is a top plan view of the ball point pen shown in FIG. 2; and

The essential features of my design reside in the portions shown in solid lines on the drawing.

The characteristic features of my design reside in a tip portion that is frusto-conical and an upper plunger portion that is cylindrical and of approximate corresponding length as the tip portion, a metallic upper barrel portion projection extending for more than one-half the length of said pen, said upper barrel cap portion being lightly scored with transverse markings and tapering inwardly along its length towards said plunger portion, and a plastic forward barrel portion located between said tip portion and upper barrel portion tapering inwardly along its length toward said tip portion all as shown.

I claim:

The ornamental design for a ball point pen, as shown and described.
